UNITED STATES PATENT OFFICE.

SANDY S. SORRENTI, OF SAN FRANCISCO, CALIFORNIA.

DOOR-OPERATING MECHANISM.

1,267,137.

Specification of Letters Patent. Patented May 21, 1918.

Application filed August 3, 1916. Serial No. 112,972.

To all whom it may concern:

Be it known that I, SANDY S. SORRENTI, a subject of the King of Italy, residing at San Francisco, in the county of San Francisco and State of California, have invented 5 certain new and useful Improvements in Door-Operating Mechanisms; and I do hereby declare the following to be a full, clear, and exact description of the invention, such 10 as will enable others skilled in the art to which it appertains to make and use the same.

This invention relates to a car door opener, and one of the objects of the invention 15 is the provision of a novel type of operating mechanism which will automatically move the door to closing position, when the car is started in motion, and will automatically move the door to open position 20 when the car is brought to a stop.

Another object of the invention is the provision of door operating mechanism, for carrying out the above object, and which will be of simple and durable construction, 25 efficient in operation, and which is particularly adapted to be applied to a street railway car of the type wherein the door has to be operated by one of the crew, so as to admit of the automatic operation of the 30 door.

Other objects will appear and be better understood from that embodiment of my invention of which the following is a specification, reference being had to the accompanying drawings forming a part thereof, 35 in which:

Figure 1 is a view of the front end of a car, showing the operating mechanism applied thereto,

40 Fig. 2 is a forward view of the door operating mechanism, showing the manner of connecting the same to a car and also to the door of the car,

45 Fig. 3 is a top plan view of a portion of the door operating mechanism,

Fig. 4 is a sectional detail view of that portion of the door operating mechanism, that returns the door to closed position, when the car is started,

50 Fig. 5 is a section on the line 5—5 of Fig. 3,

Fig. 6 is a longitudinal sectional view, taken on the line 6—6 of Fig. 3.

Referring to the drawings in detail, the letter A designates the front end of a street 55 car having a door opening B, on the side thereof, adapted to be closed by a sliding door C, which when in opened position is adapted to be received by a compartment D.

Depending from the under side of the 60 platform of the car, and located at a point near the adjacent car truck, is a pair of hangers 1, in which are journaled the opposite ends of a shaft 2. A pulley 3 is keyed 65 on the shaft 2 and a belt 4 passes around the pulley 3 and around a similar pulley, not shown, mounted on the axle of the adjacent car truck, so as to cause rotation of the shaft 2 when the axle is rotated. A bevel gear 5 is keyed to the shaft 2 at a 70 point adjacent the pulley 3, and the said gear 5 meshes with a smaller gear 6, carried by one end of a shaft 7. The shaft 7 extends at right angles to the shaft 2 and is journaled in brackets or hangers 8, which 75 depend from the under side of the platform of the car, and the opposite or outer end of the shaft 7 carries a bevel gear 9 of the size of the gear 6.

Extending at right angles to the shaft 7 80 is another shaft 12. This shaft 12 is telescopically associated with a sleeve 11. The shaft 12 is threaded for engagement with the threads 13 formed in the sleeve 11. The shaft 12 is journaled in a bracket or hanger 85 14, which depends from the under side of the car platform and which prevents longitudinal movement of the shaft 12, and the outer end of the shaft 12 carries a bevel gear 90 15, which meshes with the bevel gear 9 on the adjacent end of the shaft 7. The sleeve 11 is slidable and rotatably mounted in a bracket 16, which depends from the under side of the car platform, and arranged in spaced relation with the bracket 14, and the sleeve 11 has that end through which 95 the shaft 12 passes provided with a head 17 adapted, when the sleeve 11 is moved in a direction away from the bracket 14 to engage the bracket 16 and limit the sliding 100 movement of the sleeve 11. The sleeve 11 has that end opposite the one provided with

the head 17 reduced, as shown at 18, and the terminal of the mentioned reduced end is provided with a cylindrical head 19, which is received by a recess 20 formed in the adjacent end of a cylindrical body 21, the said end of the cylindrical body having an annular flange formed thereon, as shown at 23. A bearing collar formed of semicircular sections 24 and 25 engages 10 over the reduced end 18 of the section 11 of the shaft 10, and each of the sections 24 and 25 is provided with a semicircular flange 26, which engages the flange 23 and is secured thereto by means of fastening elements 27.

The cylindrical body 21 has the end opposite the one which carries the flange 23 bifurcated, and pivoted between the fingers of the bifurcated end of the body 21 is one 20 end of a link 28. The opposite end of the link 28 has pivotal connection with one end of another link 29, and the opposite end of the latter link is secured to one end of a shaft 30, which extends at right angles to the shaft 12, the sleeve 11 and the cylindrical body 21, and the other end of the shaft 30 has keyed thereto a bevel gear 31.

A shaft 32 extends at right angles to the shaft 30 and is journaled in hangers 33, depending from the under side of the platform of the car, and one end of the shaft 32 carries a bevel gear 34 which meshes with the gear 31 carried by the shaft 30, and the other end of the shaft 32 has connection with the lower end of an inclined rod 35, the upper end of which rod is connected to the door C.

When the car is started the belt 4 will impart rotation to the shaft 2, and the latter in turn will, through the medium of the shaft 7, cause rotation of the shaft 12, causing the sleeve 11 to be moved in the direction of the bracket 16, and cause the body 21 to rock the links 28 and 29 into the position shown in Fig. 4, thereby imparting rotation to the shaft 30, and resulting in rotation of the shaft 32 and the forward rocking of the rod 35 to the position shown in Fig. 1, so as to move the door to closed position.

It is to be understood that the threads on the inner surface of the sleeve 11 and the shaft 12 are of such pitch that one revolution of the shaft 12 will cause the sleeve 11 to travel sufficiently to bring the head 17 into engagement with the bracket 16, so as to limit the sliding movement of the sleeve 11, and it will also be noted that the length of the threaded portions on the inner surface of the sleeve 11 and on the shaft 12 are such that when the head 17 is in engagement with the bracket 16 the outer end of the threaded portion on the sleeve 11 and

the inner end of the threaded portion of the shaft 12 are in engagement in view thereof, and as the bracket 16 prevents endwise but not rotary movement of the sleeve 11, the sleeve will rotate with the shaft 12, holding the door C in closed position. It is also to be understood that the rocking of the links 28 and 29 will cause the shaft 30 to rotate in an arc sufficiently to cause about a quarter of a revolution of the shaft 32, which will be sufficient to move the door C to closed position.

A weight 36 is carried by the outer end of a depending arm 37, which is carried by the shaft 32, and when the shaft 32 has been operated to close the door C, the weight 36 and arm 37 will be moved upwardly to a horizontal position. When the car is brought to a stop the weight 36 will pull the arm 37 downwardly, rotating the shaft 32 in an opposite direction, resulting in the rotation of the shaft 30 in an opposite direction and the rocking of the links in a direction to thread the sleeve 11 back upon the shaft 12. During the rotation of the weight 36 to normal position the rod 35 will be moved rearwardly from the position shown in Fig. 1, and open the door.

It is evident that various changes might be resorted to in the construction, form and arrangement of the several parts without departing from the spirit and scope of the invention; hence I do not wish to limit myself strictly to the structure herein described and claimed.

Having thus described my invention what I claim as new, is:

1. The combination with a door and a rotatable shaft having operative connection with the door, of a second rotatable shaft, a sleeve threaded upon the second shaft and adapted to have longitudinal movement in one direction upon rotation of the second shaft, an element carried by the sleeve and having a recess therein for rotatably receiving one end of the sleeve, means for connecting the element to the first-mentioned shaft so as to effect rotation of the first shaft when the sleeve is moved in the mentioned direction so as to effect closing of the door, and means for rotating the first shaft in the opposite direction when the second shaft is at rest, so as to effect opening of the door and the return of the sleeve to normal position.

2. A door opening and closing device consisting of a rotatable shaft, means for connecting the shaft to a door, a second shaft, a sleeve threaded on and adapted to have longitudinal movement with respect to the second shaft when the second shaft is rotated in one direction, means for connecting the sleeve to the first mentioned shaft so as

to rotate the first shaft in one direction when the second shaft is rotated so as to effect closing of the door, and means for effecting rotation of the first shaft in the opposite direction when the second shaft is at rest so as to effect opening of the door and the return of the sleeve to normal position.

In testimony whereof I affix my signature in presence of two witnesses.

SANDY S. SORRENTI.
